[57] CLAIM

The ornamental design for a bag-like garment, as shown and described.

DESCRIPTION

FIG. 1 is a front, top and side perspective view of the bag-like garment showing my new design in a partially open condition;

FIG. 2 is a front elevational view thereof;

FIG. 3 is a rear elevational view thereof;

FIG. 4 is a right side elevational view thereof, it being understood that the left side is a mirror image thereof;

FIG. 5 is a top plan view thereof; and,

FIG. 6 is a bottom plan view thereof.
